DEVICE FOR RAISING SUNKEN VESSELS

William W. Scofield, Old Greenwich, Conn.

Application October 6, 1941, Serial No. 413,767

8 Claims. (Cl. 114—52)

This invention relates to a device for raising sunken vessels, such for example as submarines or the like, and has for an object to provide a device which may be controlled and operated entirely from the surface of the water. Another object is to provide a device of this character in which floats are used to provide the necessary buoyancy for raising the vessel and which floats are used for operating a series of jaws for engaging the vessel to raise it, simple means being provided for controlling or varying the buoyancy of the individual floats to control operation of the jaws and also to control lowering and raising of the device as a whole so that it may be lowered to the proper position with respect to the vessel to be raised, may be operated to engage or grip the vessel, and then be brought to the surface to raise the vessel.

With the foregoing and other objects in view I have devised a construction one form of which is illustrated in the accompanying drawings forming a part of this specification. It is however to be understood that I am not limited to the specific details and arrangement shown but may employ various changes and modifications within the scope of the invention.

In these drawings:

Fig. 1 is a side elevation showing the device floating adjacent the surface of the water over a sunken vessel in position preparatory to lowering it to engage or grip the vessel, parts being broken away to more clearly show the construction;

Fig. 2 is a similar view of the device showing it lowered to position to grip the vessel;

Fig. 3 is a similar view showing it with the jaws enclosed under and about the vessel;

Fig. 4 shows it being brought to the surface;

Fig. 5 is a view looking toward the right of Fig. 1 with parts broken away, and

Fig. 6 is a detail section through a pivot which may be used for connecting the different units.

The device comprises a series of jaws, two or more, depending on the size of the vessel to be raised, and pivoted together so that they may be swung to engage the vessel for lifting it, preferably to extend under the vessel from opposite sides thereof, together with a pair of floats connected with each jaw in a definite relation so that varying the buoyancy of the floats will operate the jaws to swing them to and from the open and closed positions and also control the raising and lowering of the device.

The device illustrated comprises four units 10 pivoted together by any suitable means, such

for example as the pivots 11 connecting adjacent units arranged side by side. The number of units may be varied depending on the effective buoyancy of each unit and the size and weight of the vessel to be raised. Each unit or assembled member comprises jaws 12 and two floats 13 and 14 connected therewith. The floats may be of different shape than that shown, but substantially the shape illustrated has been found to be very effective. The floats are substantially rectangular in cross section and the jaws 12 are mounted one on each of the opposite sides of the floats as shown, and secured thereto by any suitable means such as the rivets 15. The floats are preferably elongated hollow floats tapered so as to be wider at one end than at the other, and the float 13 is arranged in substantially upright position at one side of the pivot 11 with its smaller end at the top, while the other float 14 of each unit extends from the pivot on the opposite side thereof and is preferably inclined downwardly with its larger end lower and spaced farther from the pivot. The two floats are therefore at different angles to the horizontal, the float 13 as above stated being normally in a substantially upright position, while the float 14 is more nearly in a horizontal position.

The assembled members or units are arranged side by side with adjacent units in reversed relation so that the jaws 12 of two adjacent units extend in opposite directions from the pivots 11 and thus oppose each other, so that the free lower ends of the jaws may move toward and from each other to close and open the jaws and may extend under a sunken vessel indicated at 16 from the opposite sides thereof. The jaws on one side of the pivot may if desired be connected by a transverse bar 17 with spacing sleeves 18 between them to thus strengthen the jaws and make them more rigid in a lateral direction. The upper or smaller end of the float 14 is extended as shown at 19 somewhat up one side of the float 13 to provide a high portion of the chamber in the float to which is connected an air hose 20. A similar air hose 21 is connected to the upper part of the chamber in float 13, and preferably the inner end of the hose connection 22 extends downwardly the desired amount into the chamber or compartment so that it is not possible to permit all the air in the compartment to escape but a certain reserve will be maintained in the upper part of the compartment to give it a certain amount of buoyancy at this upper and free end of the float. At the lower part of each float 13 and 14 there are one or more

openings 23 and 24 respectively to permit flow of water to and from the compartment of the float. Air may be forced into the various floats from any suitable supply, such for example as the air pumps 25 located on any suitable vessel 26 and controlled by suitable valves 27 to either supply air to the compartments in the floats or control exit of air from these compartments. The floats are made of such a size that the aggregate buoyancy of all the floats connected together provide adequate buoyancy to lift the vessel.

The operation is as follows: With the device floating at the surface of the water it may be towed by a suitable vessel to the proper location over the known position of the sunken vessel to be raised. If the floats are all filled with air the jaws will be closed due to the buoyancy of the floats 14. If now the pressure relief valves 27 are manipulated to permit air to escape from the floats 14 and permit water to enter these floats through the openings 24, the buoyancy of these floats will be reduced and their weight will cause them to sink and this coupled with the buoyancy of the floats 13 still filled with air will swing the jaws to the open position about their pivots 11, which is the position shown in Fig. 1. This will be clear, noting that the float 14a nearest the observer connected to the jaws 12a as it becomes filled with water tends to move downwardly about the pivot 11 and swing the jaw 12a to the left or open position, and the buoyancy of the float 13a tends to raise this float and swing the jaw to the same or open position. Similarly the float 14b on the next unit as water enters tends to sink and swing its jaw 12b to the right or the open position while float 13b connected thereto, through its buoyancy tends to rise and assist in this movement.

The jaws are now in the position shown in Fig. 1, and by permitting more air to escape from the floats 14 they may be permitted to become fully filled with water. If this is not sufficient to cause the device to move downwardly in the water, air may be permitted to escape from the generally upright floats 13 permitting water to enter them through the openings 23. This of course decreases the buoyancy of these floats and will permit the whole device to sink, the weight of the floats 14 and the buoyancy of the floats 13 maintaining the jaws in the open position during this movement. As the device sinks it may be guided by suitable lines or other means from accompanying vessels on the surface of the water so that it will move downwardly in proper position directly over the vessel 16, and by controlling the exit of air the speed of the downward movement may be controlled or this movement may be stopped at any desired position to permit shifting and properly locating of the device. As the device moves downwardly as air is allowed to escape from the floats 13 it moves to the position of Fig. 2 directly over the vessel with the jaws resting on the sandy or other bottom 28. Then by pumping air into the floats 14 water is forced out of these floats through the openings 24 thereby restoring the buoyancy to these floats, and the more water is forced out the greater will be their buoyancy until it becomes sufficient for the free or lower ends of these floats to rise. They will thus swing upwardly about the pivot 11 and this assisted by the weight of floats 13 will swing the free ends of the jaws 12 toward each other and move them to a position under the vessel, as shown in Fig. 3. The buoyancy of these lower floats 14 is not enough

to raise the device as a whole because there is at this time sufficient water in the floats 13 to prevent this.

The floats are now in the position shown in Fig. 3 with the jaws closed under the vessel. Now air is forced into the floats 13 forcing the water in them out through the openings 23 and so increasing the buoyancy of these floats that together with the buoyancy of the floats 14 the combined buoyancy of all the floats is sufficient to raise the device to the surface and carry with it the sunken vessel, Fig. 4 showing the device approaching the surface of the water and carrying the vessel with it. After it has been raised to proper position, divers may enter the sunken vessel or the whole device may be towed to a harbor or shallow water and the sunken vessel deposited on the bottom in this shallow water where it is easily accessible.

The jaws 12 may be so designed that the weight of the vessel is not sufficient to open them against the action of the buoyancy of the floats 14 tending to close them, but if desired some automatic catch 29 or other device may be provided to automatically catch and hold the adjacent units together after the jaws reach the closed position. Thus a stop 30 on the float 14 may engage the inclined edge 31 on the pivoted hook 28 and force it to one side as the jaws come together in the position of Fig. 3 and then the hooks swing under the stop 30 to retain them in this position. As above stated, however, such a device is not necessary but may be used to insure that nothing will open the jaws till it is desired to do so.

As above indicated, the floats and jaws will be made of a size depending on the size of the vessel to be raised, and the number of assembled members or units to be used in any one device that will be pivoted together as shown will depend upon the length and size of the vessel as well as its weight to secure the necessary buoyancy and to grip or hold the vessel throughout the desired portion of its length. The walls of the floats may be made of relatively thin material as pressures on the inside and outside are the same, there being thus no tendency to collapse the floats, and the device may therefore be constructed of relatively light weight.

It will be seen from the above that the whole device and its manipulation may be controlled from above the water by controlling the supply of air in the various floats, and it is therefore not necessary to have a diver go down to connect chains or other devices to the vessel to be raised. The jaws will force themselves through the sand to extend under the vessel. This control not only controls the lowering and raising of the device, but it also controls the opening and closing of the jaws, and the position of the device may be readily controlled so that it may be lowered to the most advantageous position for engaging the vessel. After the sunken vessel is located its location may be marked by suitable buoys and then this device towed to proper position over the vessel and then lowered and at all times held in proper position and its movements accurately and readily controlled during the lowering operation. It is as readily controlled to engage or grip the vessel and then raise it and to carry it to any location desired.

Having thus set forth the nature of my invention, what I claim is:

1. A device of the character described comprising opposed members pivoted together in re-

versed relation, each member comprising a pair of hollow floats extending in opposite directions from said pivot, jaws on said members adapted to extend from opposite sides under a sunken vessel, means for supplying air to and releasing it from the upper portions of said floats, and means at the lower part of said floats for flow of water to and from the floats.

2. A device of the character described comprising jaws pivoted together and adapted to extend under a sunken vessel from opposite sides thereof, a pair of elongated hollow floats connected to each jaw, one of said pair extending in a generally upright position at one side of the pivot and the other being inclined downwardly away from the pivot on the opposite side thereof, means for supplying air to and releasing it from the higher portions of said floats, and means for permitting flow of water to and releasing it from the lower portions of said floats.

3. A device of the character described comprising jaws pivoted together and adapted to extend under a sunken vessel from opposite sides thereof, a pair of hollow floats connected to each jaw, one of said floats located on one side of the pivot so that when filled with air its buoyancy tends to move the jaw connected therewith to a position under the vessel, the other float being located on the opposite side of the pivot so that when filled with air its buoyancy tends to move the jaw in the opposite direction, means for supplying air to and releasing it from the higher portions of said floats, and means for permitting flow of water to and releasing it from the lower portions of said floats.

4. A device of the character described comprising jaws pivoted together to swing to and from closed position, said jaws adapted when closed to extend under a sunken vessel from opposite sides thereof, a pair of elongated hollow floats connected to each jaw, one of which floats is in a generally upright position on one side of the pivot and when filled with air tends to move its jaw to the open position and the other of said floats extending away from the pivot on the opposite side thereof and when filled with air tends to move the jaw to closed position, means for supplying air to and releasing it from the higher portions of said floats, and means for permitting flow of water to and releasing it from the lower portions of said floats to change the buoyancy thereof.

5. A device of the character described comprising jaws pivoted together to swing to and from closed position, said jaws adapted when closed to extend under a sunken vessel from opposite sides thereof, a generally upright hollow

float connected to each jaw and located on the same side of the pivot as the jaw so that its buoyancy tends to swing the jaw to open position, a second hollow float connected to each jaw and located on the opposite side of the pivot from the jaw so that its buoyancy tends to move the jaw to closed position, means for supplying air to and releasing it from the upper portions of said floats, and said floats having openings in the lower portions thereof to permit water to enter and leave the floats to change the buoyancy thereof.

6. A device of the character described comprising a pair of pivoted jaws extending in opposite directions from the pivot to swing to and from open and closed positions, a pair of elongated hollow floats connected to each jaw and arranged one on each of the opposite sides of the pivot so that one of said floats by its buoyancy tends to swing its connected jaw to open position and the other float by its buoyancy tends to swing it to closed position, each float having an opening in the lower portion thereof for entrance and exit of water to vary the buoyancy thereof, and means for supplying air to and releasing it from the upper portion of the floats to control the amount of water in the floats.

7. A device of the character described comprising a pair of jaws pivoted together to extend in opposite directions from the pivot to swing to and from open and closed positions and adapted when closed to engage a sunken vessel, a pair of elongated hollow floats connected to each jaw, one of the floats of each jaw extending in a generally upright position on one side of the pivot so that its buoyancy tends to open the jaw, the other float extending from the opposite side of the pivot and inclined downwardly so that its buoyancy tends to close the jaw, each float having an opening in the lower part thereof for entrance and exit of water to vary the buoyancy of the float, and means for supplying air to and releasing it from the upper portions of the floats to control the amount of water in the floats.

8. A device of the character described comprising jaws pivoted together to swing to and from open and closed positions and adapted when closed to engage a sunken vessel for raising it, a pair of floats connected to each jaw and located on opposite sides of the pivot so that the buoyancy of one float tends to open the jaw and the buoyancy of the other float tends to close it, and means for varying the buoyancy of the floats to control the opening and closing of the jaws and raising and lowering of the device.

WILLIAM W. SCOFIELD.
